UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

FLAT-BED WEB-PRINTING PRESS.

1,259,975.

Specification of Letters Patent. Patented Mar. 19, 1918.

Application filed November 8, 1916. Serial No. 129,378.

To all whom it may concern:

Be it known that I, SAMUEL G. Goss, a citizen of the United States, and a resident of Glencoe, in the county of Cook and State 5 of Illinois, have invented certain new and useful Improvements in Flat-Bed Web-Printing Presses, of which the following is a specification, reference being had to the accompanying drawings.

10 My invention relates to flat-bed web printing presses in which an impression cylinder is reciprocated along a flat printing surface, being adapted to have an operative printing stroke in one direction, being moved in the 15 opposite direction in raised position relative to the printing surface. It is the principal object of my invention to provide new and improved means for raising the impression cylinder from the bed at the end of the operative stroke and for again lowering the impression cylinder at the end of the inoperative stroke. It is another object of my invention to provide a construction by which the vertical movement of the impression cylinder into and out of operative position shall be controlled by the rotation of the cylinder. 25 It is another object of my invention to improve devices of this type in sundry details hereinafter pointed out. The preferred 30 means by which I have accomplished my several objects are illustrated in the drawings and are hereinafter specifically described. That which I believe to be new and desire to cover by this application is 35 set forth in the claims.

In the drawings:—

Figure 1 is a diagrammatic side view of a press illustrating the type of machine for which my improvements are designed;

40 Fig. 2 is a side view of a portion of a press equipped with my improved mechanism showing the impression cylinders in operative position just at the beginning of the operative stroke;

45 Fig. 3 is a view similar to Fig. 2, but showing the impression cylinders in raised position substantially at the beginning of an inoperative stroke;

50 Fig. 4 is a view of the mechanism at the end of the upper impression cylinder in Fig. 2 as seen from the right in said figure;

Fig. 5 is a top view of an arm mounted upon the shaft of the impression cylinder as the same is seen in Fig. 2; and

55 Fig. 6 is a view similar to Fig. 2, but showing a modified form of construction.

Referring to Figs. 1 to 5 in which corresponding parts are indicated by the same reference characters,—

10 indicates a frame, supporting type 60 beds or other printing surfaces 11—12 of any suitable character. A carriage 13 is slidably mounted upon the frame 10, being adapted to be reciprocated back and forth along the beds 11 and 12 by means of connecting links 14 which are actuated by drive wheels 15 rotated by power from any suitable source.

Revolutely mounted in the carriage 13 at each side of the press is an eccentric 16 in 70 which is revolutely mounted eccentrically thereof a shaft 17 upon which is fixed an impression cylinder 18 adapted to be reciprocated along the bed 11. The carriage 13 is also provided with eccentrics 19 revolu-

bly mounted therein at its sides, in which is revolutely mounted eccentrically thereof a shaft 20 upon which is fixed an impression cylinder 21. The eccentrics 16 and 19 at each side of the machine are connected together by means of a vertical link 22 which connects arms 23—24 carried by said eccentrics respectively. As will be readily understood, as the eccentrics 16 and 19 are rotated in counterclockwise direction in Fig. 85 2, the shafts 17 and 20 are raised relative to the beds 11—12. The eccentric 16 is provided with an arm 25 to which the upper end of a coiled spring 26 is connected, the other end of such spring being connected to a suitable portion of the carriage 13, the spring 26 being adapted to hold the eccentrics 16 and 19 turned to the limit of their rotation in counterclockwise direction in Fig. 2, serv-

ing thus to hold the impression cylinders 18 95 and 21 yieldingly in raised position. Each of the impression cylinders 18 and 21 is provided with a gear 27 at each end which meshes with a rack-bar 28 in suitable position upon the stationary part of the framework whereby such cylinders will be rotated in one direction upon the operative stroke and in the reverse direction upon the inoperative stroke, as is well understood in 100 presses of this type.

105 Means is provided for moving the cylinders downward at the end of their inoperative stroke against the action of the spring 26 and for holding the cylinders in their lowered position during the operative stroke. 110 This means comprises arms 29 mounted upon the ends of the shaft 17, the arms 29 being

provided on their inner faces with lugs 30 which are adapted to be brought into contact as hereinafter described with lugs 31 carried on the outer faces of the arms 23. 5 As is best shown in Fig. 2, the lugs 30 and the arms 29 are so arranged relative to the impression cylinder 18 that the lug 30 is brought into contact with the upper face of the lug 31 substantially at the end of the 10 movement of the carriage 13 to the right in Fig. 2, serving to move the arm 23 downward against the action of the spring 26. The arm 23 is provided with a latch lever 32 which is moved at this juncture by a 15 spring 33 in clockwise direction in Fig. 2 into engagement with a notch 34 in an arm 35 carried by the carriage 13, the engagement of the latch lever with the arm 35 serving to hold the eccentric 16 against movement in counterclockwise direction in said figure and serving thus to hold the impression cylinder 18 in its lowered operative position during the movement of said cylinder to the left in said figure. Upon the 20 movement of the cylinder to the left in Fig. 2, the cylinder will be given a rolling rotation in counterclockwise direction in said figure, bringing the lug 30 in due time into contact with the lower face of the lug 31 as 25 shown in Fig. 3 for moving the eccentric 16 positively in counterclockwise direction for raising the cylinder 18 out of operative position. This action is made possible by a pin 36 mounted upon the arm 29 which engages 30 an arm 37 mounted upon the shaft 38 upon which the latch 32 is mounted for moving said lever against the action of the spring 33 out of engagement with the notch 34 of the arm 35 so as to permit the desired movement 35 of the eccentric 16. As will be readily understood, by reason of the connection of the eccentrics 16 and 19 through the link 22, the cylinders 18 and 21 are moved up and down in unison. By reason of the engagement 40 of the lug 30 with the lug 31 substantially at the time when the connecting links 14 are at their dead-center position and when the carriage 13 is accordingly moving at a very slow rate, the operative engagement is 45 effected without injury to the parts.

50 In Fig. 6 which illustrates a modified construction, the link 22 at each side of the machine is omitted, and the mechanism for controlling the cylinder 18 is duplicated in connection with the cylinder 21. For convenience, in the construction shown, a coiled spring 39 is connected to the forward end of the arm 24 of the eccentric 19 for holding the eccentric yieldingly against clockwise 55 movement in said figure, in lieu of the spring 26 as described in connection with the eccentric 16. Otherwise the construction is 60

practically the same and the operation is exactly similar.

What I claim as my invention and desire 65 to secure by Letters Patent, is—

1. In a printing press, the combination of a bed, an impression cylinder, means for reciprocating said cylinder along said bed, means for rotating said cylinder, and means actuated by the rotation of the cylinder at substantially the end of the movement of the cylinder in one direction along said bed for raising the cylinder out of operative position for its inoperative stroke along the bed. 70

2. In a printing press, the combination of a bed, a carriage, eccentrics revolubly mounted in said carriage, an impression cylinder revolubly mounted between said eccentrics, means for reciprocating said carriage for carrying said cylinder along said bed, means for rotating said cylinder, and means actuated by the rotation of the cylinder for turning said eccentrics for raising the cylinder out of operative position at the end 75 of the operative stroke.

3. In a printing press, the combination of a bed, a carriage, eccentrics revolubly mounted in said carriage, an impression cylinder revolubly mounted between said eccentrics, means for reciprocating said carriage for carrying said cylinder along said bed, means for rotating said cylinder, arms carried around by the rotation of said cylinder adapted at the end of an inoperative stroke 90 of the cylinder to engage said eccentrics and give them a slight rotation for moving said cylinder downward into operative position, and latches operatively connected with said eccentrics adapted automatically to engage 95 suitable portions of said carriage for maintaining the cylinder in lowered operative position.

4. In a printing press, the combination of a bed, a carriage, eccentrics revolubly mounted in said carriage, an impression cylinder revolubly mounted between said eccentrics, means for reciprocating said carriage for carrying said cylinder along said bed, means for rotating said cylinder, latches 105 pivotally mounted on said eccentrics and adapted to engage said carriage for holding the eccentrics in turned position for maintaining the cylinder in lowered operative position, and arms carried around by the rotation of said cylinder adapted at the end of an operative stroke of the cylinder to release 110 said latches from said carriage for permitting rotation of the eccentrics and adapted to engage said eccentrics and give them a 115 slight rotation for raising said cylinder out of operative position.

SAMUEL G. GOSS.
